UNITED STATES PATENT OFFICE.

GEORGE S. THOMPSON, OF HOPKINTON, MASSACHUSETTS, AND CHARLES F. RICHARDSON, OF WOONSOCKET, RHODE ISLAND, ASSIGNEES TO THOMPSON ENGINE STARTER COMPANY, OF NEW YORK, N. Y., A CORPORATION OF NEW YORK.

ENGINE-STARTER.

1,186,956.

Specification of Letters Patent. Patented June 13, 1916.

Application filed May 29, 1913. Serial No. 770,621.

To all whom it may concern:

Be it known that we, GEORGE S. THOMPSON and CHARLES F. RICHARDSON, citizens of the United States, residing at Hopkinton, county of Middlesex, Massachusetts, and Woonsocket, county of Providence, Rhode Island, respectively, have invented certain new and useful Improvements in Engine-Starters, of which the following is a full, clear, and exact description.

The invention which constitutes the subject matter of this application relates to an automatic engine starter and while the embodiment of the invention herein described and illustrated in the accompanying drawings is specially designed for cranking the engine of an automobile, it will be obvious that the invention is not confined to this specific use.

Referring to the drawings which show one of the embodiments of our invention, Figure 1 is a view in perspective to show one convenient method of mounting the starter. Fig. 2 is an enlarged cross-sectional view of the starter mechanism. Fig. 3 is a longitudinal section on the line 3—3 of Fig. 2. Fig. 4 is a cross-section of that part of the mechanism which is mounted upon the engine shaft showing the housing in which parts of this mechanism operate. Fig. 5 is a section taken on the line 5—5 of Fig. 4. Figs. 6 and 7 are details of the clutching mechanism which is mounted on the power shaft.

The characters 10 and 100 designate suitable housings in which the starting mechanism is confined, and operates, and, as will be readily seen from the drawings, a part of this mechanism is mounted upon the crank shaft and the other part is mounted upon the engine supports 11 and located at one side of the engine 12 just under the bonnet (not shown), thus giving ready access to the various parts of the starter when desired.

Preferably fixed upon the engine shaft 13 is a sprocket gear 14 over which a sprocket chain 15 of the silent type is adapted to operate, the latter in turn being connected to a gear 16 loosely encircling a rotatable power shaft 17 which is suitably journaled in the housing 10. Mechanism operatively connected to the gear 16 is provided for automatically cranking the engine and also mechanism for restoring, in

turn, power in the spring. We will now proceed to describe in detail these respective means for cranking the engine and restoring power in the power spring.

Located in proximity to the gear 16 and 60 rotating around the power shaft 17 in unison therewith is another gear 18. This gear 18 is riveted to or otherwise secured to gear 16 and so far as the cranking of the engine is concerned it performs no particular function but is essential in the restoration 65 of power in the power spring. The gear 16 carries a plurality of spring pressed plungers or pawls 19 which are located in sockets 20, as clearly shown in Figs. 3 and 70 7. The pawls are preferably provided with ears 21 which slide in grooves 22 of said gear. These ears and grooves effectually prevent rotation of the plunger relative to said gear. The gear 18 is provided with 75 annular perforations 23 through which the rearward end of said plungers project. Located in the forward end of each of the sockets 20 is a suitable spring 24 which has a tendency to urge the pawl rearwardly. 80 This rearward movement of the pawl is limited by the fact that one end of the rib 21 comes into contact with the forward side of the gear 18, it being understood that the pawl is so shaped at its rearward end as to 85 effect a snug fit with the perforation in the gear 18. It is to be understood that the construction of the gears 16—18 and pawls 19 which prevents the latter from rotating relatively to the former is the one that is 90 preferred, and is here shown and described as one of the many constructions that may be resorted to in manufacturing our starter without departing from the true scope of 95 our invention.

Located upon the power shaft 17 and fixed to rotate therewith is a clutch member 25 which is capable of longitudinal movement with respect to this shaft. This member is provided with laterally projecting 100 ratchet teeth 26 which are adapted to be engaged with and disengaged from the pawls 19, protruding through gear 18, whenever the said member is moved longitudinally upon said power shaft. Loosely 105 mounted upon the power shaft is a worm wheel 27 provided with laterally projecting teeth 28 which are adapted to normally engage corresponding sockets 29 in the clutch member, the said teeth and sockets effecting 110

an interlocking engagement between the said worm wheel and the said clutch member and said engagement being maintained until one of said elements is moved relative to the other. The rear end of the power shaft is connected to and is operated by the power spring 30. For the sake of convenience, the part 31 of the shaft to which the spring is connected, may be disconnectible from the main power shaft at the point 32.

The clutch member is provided with a peripheral flange 33 adapted to be constantly engaged by a forked member 34 having a groove 35 on the interior thereof which corresponds in shape to the shape of the peripheral flange. This forked member is preferably fixed to a shaft 36, which is adapted to be moved longitudinally by means of a lever 37 pivoted at 38 upon the housing 10. A spring 39 is employed to hold the upper end of this lever in its forward position, which in turn serves to hold the clutch member normally in interlocking engagement with the worm wheel 27 as clearly illustrated in Fig. 3. To the upper end of the lever 37 is connected a wire rope or cord 40 extending through the dashboard of the machine and there connected to suitable foot-operated mechanism for effecting a rearward pull upon the lever 37.

As before stated the sprocket gear 14 is loosely mounted upon the crank shaft 13. This gear is provided with spring pressed plungers or pawls 41 which are normally out of engagement with the member 42 fixed upon the crank shaft. The forward ends of the pawls 41 are adapted to enter sockets 43 in the said member 42, but are normally held out of engagement therefrom, to permit the said member to rotate idly, by means of a cam sleeve 44 provided with cam surfaces 45. Fixed to the frame and surrounding the crank shaft is an annular member 46 whose outer periphery is provided with a plurality of cam rollers 47 which coöperate with the cam surfaces 45 to move the sleeve longitudinally with respect to the fixed member 42. The sleeve, engaging as it does with the forward ends of pawls 41, normally holds the latter out of engagement with the sockets 43. To the sleeve is secured a stud 48 which is connected with a lever 49 mounted upon a rock shaft 50 by means of a link 51, said lever and the said link being preferably located within the housing 100. To one end of the rock shaft 50 is secured an arm 52 provided with a stud 53 adapted to engage behind shoulder 54 on lever 55. When the arm is moved so as to throw the sprocket wheel into clutching engagement with the fixed member upon the crank shaft, the lever 55 is cammed outwardly about its pivot 56 and as soon as the said arm is moved sufficiently in that direction by a suitable cord 57 connected to the

foot operated means, the shoulder on the lever will drop behind the stud and prevent its return. When released, however, by mechanism to be described later, the spring 58 returns the said sleeve to normal position thus unclutching the member 42 from sprocket gear 14.

When the spring is wound up, let it be assumed that certain instrumentalities are connected with the worm wheel 27 for holding the same stationary, and inasmuch as the clutch member is fixed to the power shaft and is in interlocking engagement with the worm wheel, obviously no unwinding can take place and the operation in cranking the engine is as follows: When the lever 37 is pulled to its rearward position, by convenient foot-operated mechanism, it disengages the clutch member 25 from the worm wheel 27 but before it is completely disengaged therefrom the lateral teeth 26 on the clutch member are beginning to engage with the spring pressed pawls 19. Consequently, when the clutch member 25 is completely disengaged from the worm wheel 27, it is in effective operative engagement with gears 16-18 and the power spring 31 now acts, through the power shaft and clutch member, to rotate the gears 16-18 to crank the engine, the power spring and gears 14-16 being so constructed as to impart about eight revolutions to the crank shaft in the operation of cranking the engine. The arm 52 is simultaneously actuated by means of the foot-operated mechanism to rotate the sleeve 44 and thus allow the spring pressed pawls to move the same forwardly which is permitted by means of the cam surfaces 45 and cam rollers 47 to effect an interlocking engagement between the pawls of the sprocket gear 14 and the sockets in the fixed member 42, the parts being so constructed that this clutching engagement is effected before the member 25 is released from its engagement with the worm wheel 27. The link 51 is bifurcated as indicated at 49 and the projecting stud 48, mounted as it is upon the pivot pin 60, has a longitudinal movement with respect to the crank shaft but this movement is limited by the bifurcated arms 49. During the cranking of the engine the teeth on the clutch member 25 are held in engagement with the pawls 19 by the turning force of the latter, or by continued tension on lever 37 by means of foot pedal. But as soon as the engine is cranked the pawls, owing to their peculiar formation, run "ahead" of the teeth on the clutch member, thus permitting the latter to be retrieved, by means of the spring 39 connected to lever 37, into interlocking engagement with worm wheel 27. Those parts that have not been previously described are now in position to effect a rewinding of the power spring.

Having described the mechanism and the

operation thereof for cranking the engine, we will now proceed to describe the mechanism associated with the aforesaid mechanism for the restoration of power in the power spring. Suitably journaled in the housing 10 in proximity to and substantially parallel with the power shaft is a counter shaft 61 upon which is fixed a toothed gear 62 constantly in mesh with and actuated by the gear 18. Also fixed to this shaft is a spiral gear 63 meshing with a similar gear 64 fixed upon one end of the vertical shaft 65. This vertical shaft is suitably journaled in the housing and upon its other end is fixed the worm gear 66 which meshes with and operates the worm wheel 27 previously described.

Assume for the moment that the parts are in interlocking engagement with the fixed member 42, as above described, and that the engine is cranked; the operation of the device in restoring energy in the power spring is as follows: As before stated, the member 25, as soon as the engine has been cranked, is retrieved from the sprocket gears 16-18 and is brought again into interlocking engagement with the worm wheel 27 by means of the spring 39. A rotative movement is imparted to the fixed member 42 by means of the engine, which in turn operates the sprocket gears 14, 16-18 and toothed gear 62. The latter, as before stated, is fixed upon the counter shaft 61 and as a result rotative movement is imparted to the latter. This rotative movement in turn transmits a rotative movement to the spiral gears 63, 64, worm gear 66, and worm wheel 27. The member 25 being fixed upon the power shaft, a rotative movement is also imparted there-to to rewind the power spring, it being readily understood from the above description that in cranking the engine the power shaft is rotated in one direction, while in restoring energy in the power spring the power shaft is operated in the opposite direction.

The mechanism for effecting a positive engagement between the sprocket gear 14 and the member 42 has been previously described. We will now proceed to describe an automatic means for effecting a disengagement of said elements after sufficient energy has been stored in the power spring. The power shaft is provided with a screw-threaded portion 67 upon which a screw-threaded arm 68 is located and adapted to be moved longitudinally whenever the said shaft is operated in either direction. The normal position of the parts is indicated in Fig. 2. A flexible connection 69 is provided between the lever 55 and the arm 68. When the foot mechanism is operated to release the power spring the pawl 53 simultaneously engages behind the shoulder 54 to effect a clutching engagement between the fixed member 42 and the sprocket gear 14. The power shaft then begins

to rotate and moves the screw threaded arm 68 longitudinally in the direction indicated by the arrow *a*. The arm has a tendency, due to friction, to rotate in the direction indicated by the arrow *b*, but to avoid this a suitable stop 70 is employed. As soon as the engine is cranked, or more accurately stated, as soon as the member 25 is again brought into clutching engagement with the worm wheel 27, the restoring operation begins. The power shaft is now being rotated in the opposite direction and the arm 68 is now moving in a direction opposite to that indicated by the arrow *a*. This movement of the arm continues until the same has traveled so to the ends of the threads and fits the stud 71, which in the present instance will be accomplished by substantially eight revolutions of the power shaft. The arm will now be rotated in unison with the power shaft and thus move the lever 55 by means of the flexible connection 69 when the pawls 53 will be released from the shoulder 54 and the spring 58 will turn the cam sleeve 44 to un-clutch the member 42 and sprocket gear 14 as previously described.

The fixed member 42 on the engine shaft is operated by the spring actuated means to crank the engine and in turn operates the spring actuated means to store up energy in the spring. As soon as the said fixed member is released from operative engagement with the spring actuated mechanism after energy has been stored in the power spring, it will be necessary to hold the said spring actuated mechanism against operation. This we accomplish by the arrangement of the spiral gear and the worm gear on the vertical shaft 65, as it will be understood motion can be imparted to the worm wheel 27 only by the rotation of the worm gear in mesh therewith. It will also be apparent that the pressure from the worm wheel upon the worm gear acts upon the threads of the latter at substantially right angles to the direction of the same. Consequently, there can be but little if any rotative movement acting upon the worm gear. If there be a rotative movement, it is so slight that its effect is *nil*. It will therefore be seen that we have eliminated the extraneous or rather the independent holding mechanism which is ordinarily used in engine starters. The worm wheel and worm gear have therefore a dual function, namely, to hold the spring actuated mechanism against rotation and to coöperate with other mechanism to store up energy in the power spring. This not only reduces the number of parts to a minimum, but also insures a better operation of the starter.

From the above description it will be observed that after the engine is cranked and energy restored in the power spring the only part that operates, so long as the engine continues to run, is the fixed member 42 on the

engine shaft, but as this member is out of engagement with the other parts of the starter there can be no wear outside of that which occurs during the brief interval of time required to crank the engine and restore energy in the power spring. The housing 100 which incloses the mechanism on the engine shaft is preferably made fluid tight whereby the parts may run in oil and thus the wear, during the cranking and storing operations may be reduced as much as possible.

It is to be understood that we do not limit ourselves to the particular embodiment 15 which we have chosen to illustrate as our invention, as it is perfectly obvious, in the light of the foregoing description taken in connection with the construction herein shown, that various other modifications may 20 be resorted to and minor changes made without necessarily departing from the true spirit and scope of our invention.

What we claim is:

1. In an engine starter, an engine shaft, 25 a sprocket gear loosely mounted upon said shaft, and a clutch member fixed upon said shaft and adapted to be operatively connected with said sprocket gear, in combination with starting mechanism for operating said sprocket gear and clutch member to 30 crank the engine, said mechanism comprising a power shaft, a sprocket gear rotatably mounted upon said power shaft, means for operatively connecting said sprocket gears, 35 a clutch member rotatably fixed to said power shaft but capable of longitudinal movement thereon, the second mentioned sprocket gear and clutch member provided with means for effecting an interlocking engagement between the same as one is moved 40 toward the other, means normally engaging said last mentioned clutch member to hold the latter stationary, and mechanism for moving the last mentioned clutch member 45 cut of engagement with the last mentioned means and into clutching engagement with the sprocket gear to crank the engine.

2. In an engine starter, an engine shaft, 50 a sprocket gear loosely mounted upon said engine shaft, a clutch member fixed to said shaft and adapted to be operatively connected to said sprocket gear, in combination with a power shaft, a sprocket gear rotatably mounted upon said power shaft, and 55 means for operatively connecting the sprocket gear on the power shaft with the sprocket gear on the engine shaft; in combination with means for rotating the sprocket gear on the power shaft to crank 60 the engine, said means comprising a clutch member rotatably fixed to said power shaft but capable of longitudinal movement thereon, means normally engaging said clutch member to hold the same stationary, and means for moving the clutch member 65

longitudinally of said power shaft out of engagement with the last mentioned means into clutching engagement with the sprocket gear, whereby the power shaft is permitted to rotate the clutch member and sprocket 70 gear thereon to crank the engine.

3. In an engine starter, an engine shaft, a sprocket gear loosely mounted upon said engine shaft, means for operatively connecting the sprocket gear to the crank shaft, 75 a power shaft, a sprocket gear mounted upon said power shaft, and means operatively connecting said sprocket gears; in combination with means for rotating said sprocket gear on the power shaft to crank the engine, 80 said means comprising a clutch member rotatably fixed to said shaft but capable of longitudinal movement thereon, means normally engaging said clutch member to hold the same stationary, and means for moving 85 the clutch member longitudinally of said shaft to release the same from said engaging means and to bring the same into clutching engagement with the sprocket gear, said clutching engagement being established 90 before the clutch member is released from its holding means, substantially as described.

4. In an engine starter, an engine shaft, a sprocket gear loosely mounted upon said engine shaft, means for operatively connecting the sprocket gear with the engine shaft to crank the engine, a power shaft, a sprocket gear mounted upon said power shaft, and means for operatively connecting 95 said sprocket gears; in combination with means for actuating said sprocket gear on the power shaft to crank the engine, said means comprising a clutch member rotatably fixed to said power shaft but capable of longitudinal movement thereon, means normally engaging said clutch mechanism to hold the same stationary, means for moving 100 the clutch member longitudinally of said shaft to release the same from said engaging means and to bring the same into clutching 105 engagement with the sprocket gear for rotating the latter to crank the engine, and means for automatically moving the clutch member in the opposite direction after a certain number of rotations of said sprocket 110 gear to disengage the same from the sprocket gear and to cause the same to reengage the aforesaid holding means.

5. In an engine starter, an engine shaft, a sprocket gear loosely mounted upon said engine shaft, means adapted to operatively connect the sprocket gear with the engine shaft when it is desired to crank the engine, a power shaft, a sprocket gear loosely mounted upon said power shaft, means for 120 operatively connecting the said sprocket gears, and means for rotating the sprocket gear on the power shaft to crank the engine, said means comprising a clutch member rotatably fixed to said power shaft but ca- 125 130

- 5 pable of longitudinal movement thereon, means normally engaging said clutch mechanism to hold the same against rotation, means for moving the clutch member longitudinally of said shaft to release the same from said engaging means and to bring the same into clutching engagement with the sprocket gear to rotate the latter to crank the engine, and means for automatically returning the clutch member to normal position, in combination with means connected to and operated by said sprocket gear after the engine is cranked for rotating said clutch member to restore energy in the 15 power spring.
6. In an engine starter, an engine shaft, a sprocket gear loosely mounted upon said engine shaft, and means adapted to operatively connect the sprocket gear with the engine shaft, in combination with means for rotating said sprocket gear to crank the engine, said means comprising a spring actuated power shaft, a sprocket gear rotatably mounted upon said power shaft and operatively connected to the aforesaid sprocket gear, a clutch gear rotatably fixed to said power shaft but capable of longitudinal movement thereon, rotatable means normally engaging said clutch mechanism to hold the latter stationary, means for moving the said clutch mechanism out of engagement with the said rotatable means into clutch engagement with the sprocket gear on the power shaft whereby the said gear and the sprocket 35 gear on the engine shaft are rotated to crank the engine, means for automatically returning the clutch member to normal position in engagement with said rotatable holding means, and means connected to and operated by the sprocket gear on the power shaft after the engine has been cranked for rotating said clutch member to restore energy in the power spring.
7. In a starting apparatus for explosive engines, an engine shaft, a sprocket gear loosely mounted upon said shaft, and means for operatively connecting the sprocket gear to the engine shaft, in combination with a power shaft operated by power means, a sprocket gear loosely mounted upon said power shaft and operatively connected to the aforesaid gear, means on said power shaft operated in one direction by the power means to rotate the sprocket gears to crank the engine, and mechanism connected to the sprocket gear on the power shaft and actuated by the said gear after the engine has been cranked for operating the aforesaid means in the opposite direction to store up 50 energy in the power spring.
8. In a starting apparatus for explosive engines, an engine shaft, a sprocket gear loosely mounted upon said shaft, means for operatively connecting the sprocket gear with the engine shaft, a spring actuated power shaft, a sprocket gear mounted upon said power shaft and operatively connected to the gear with engine shaft; in combination with means actuated by the said sprocket gear on the power shaft after the engine has been cranked to restore power in the power means, comprising a gear rotatably mounted upon the power shaft, a clutch member fixed to said shaft and normally in interlocking engagement with the last mentioned gear, and mechanism operatively connecting the sprocket gear on the power shaft and the last mentioned gear.
9. In a starting apparatus for explosive engines, an engine shaft, a sprocket gear loosely mounted upon said engine shaft, means for operatively connecting the said gear with the engine shaft, a spring actuated power shaft, a sprocket gear loosely mounted upon said power shaft, and means for operatively connecting the sprocket gears; in combination with means operatively connected to said sprocket gear on the power shaft and actuated by the engine after the latter has been cranked to restore power in the power means, comprising a gear wheel rotatably mounted upon the power shaft, a clutch member fixed to said shaft and in interlocking engagement with the last mentioned gear, a counter shaft, a toothed gear fixed thereon and operatively connected to the sprocket gear on the power shaft, and means operatively connecting said toothed gear and the said gear wheel.
10. In a starting apparatus for explosive engines, an engine shaft, a sprocket gear loosely mounted upon said shaft, means for operatively connecting said gear with the engine shaft, a spring actuated power shaft, a sprocket gear loosely mounted upon said power shaft, and means for operatively connecting the sprocket gears; in combination with means operatively connected to said sprocket gear on the power shaft and actuated by the engine after the latter has been cranked to restore power in the power means, comprising a gear wheel rotatably mounted upon the power shaft and normally in interlocking engagement with the last mentioned gear, a counter shaft located parallel and adjacent to the power shaft, a toothed gear fixed to said counter shaft, and operatively connected to the sprocket gear on the power shaft, a spiral gear fixed to said counter shaft and operated thereby, a gear located upon a vertical shaft and meshing with said spiral gear and operated by the latter, and a worm gear also on said vertical shaft and meshing with the worm gear on the power shaft for operating the latter.
11. In a starting apparatus for explosive engines, an engine shaft, a sprocket gear loosely mounted upon said shaft, means for operatively connecting said gear with said engine shaft, in combination with

power means operatively connected to said sprocket gear for cranking the engine and mechanism associated with the aforesaid means and actuated by the engine after the latter has been cranked to restore power in the power means; said cranking means comprising a power shaft, a sprocket gear rotatably mounted upon said power shaft and operatively connected to the 5 sprocket gear on the engine shaft, and means adapted to engage with and rotate said sprocket gears to crank the engine; and said restoring mechanism comprising a gear wheel rotatably mounted 10 upon the power shaft and normally in engagement with the last mentioned means, a counter shaft arranged adjacent to said power shaft, a toothed gear fixed on said shaft and operatively connected to the said 15 sprocket gear, and means connected to said gear wheel, and actuated by said toothed gear, whereby the said gear wheel and the said means in normal engagement therewith are rotated by said toothed gear to restore 20 energy to the power means.

12. In a starting apparatus for explosive engines, an engine shaft, a sprocket gear loosely mounted upon said shaft, means for operatively connecting the said gear with 25 said engine shaft, and cranking means operatively connected to said sprocket gear, comprising a spring actuated power shaft, a sprocket gear rotatably mounted on said power shaft, and means adapted to engage with and rotate said sprocket gears to crank the engine, in combination with mechanism operated in turn by the engine for restoring energy to the spring after the engine has been cranked, comprising a gear 30 wheel rotatably mounted on the power shaft and normally in engagement with the last mentioned means, a counter shaft arranged adjacent to said power shaft, a toothed gear fixed thereon and operatively connected to the 35 sprocket gear on the power shaft, and means operatively connecting said toothed gear and said gear wheel, whereby the latter and said means in normal engagement therewith are rotated by the former to restore 40 energy in the power means.

13. In a starting apparatus for explosive engines, an engine shaft, a sprocket gear loosely mounted upon said shaft, means for operatively connecting said gear to said 45 engine shaft, cranking means operatively connected to said sprocket gear, comprising a spring actuated power shaft, a sprocket gear rotatably mounted upon said power shaft and operatively connected to the aforesaid sprocket gear and a member slidably mounted upon and rotatably fixed to said power shaft, adapted to be brought into engagement with and to rotate said sprocket gears to crank the engine, in combination 50 with mechanism operated in turn by the en-

gine for restoring energy in the spring after the engine has been cranked, comprising a counter shaft arranged adjacent to said power shaft, a toothed gear fixed thereon and operatively connected to said sprocket gear on the power shaft, and means operatively connecting said toothed gear and said member, whereby the latter is rotated by the former to restore energy in the power means. 70

14. In a starting apparatus for explosive engines, an engine shaft, a sprocket gear loosely mounted upon said shaft, means for operatively connecting said gear with said engine shaft, cranking means operatively connected to said sprocket gear, comprising a spring actuated power shaft, a sprocket gear rotatably mounted upon said power shaft and operatively connected to the aforesaid gear, and a member adapted 80 to be brought into operative engagement with the sprocket and operated in one direction by the spring actuated power shaft to crank the engine, in combination with means adapted to operatively connect said member with the sprocket gear on the power shaft, and actuated by the latter after the engine has been cranked to rotate said member in the other direction to store 85 up energy in the power shaft. 90

15. In a starting apparatus for explosive engines, an engine shaft, a sprocket gear loosely mounted upon said shaft, means for operatively connecting said gear with said engine shaft, cranking means operatively connected to said sprocket gear, comprising a spring actuated power shaft, a sprocket gear rotatably mounted upon said power shaft, and a member adapted to be brought into operative engagement with the sprocket gear and operate in one direction by the spring actuated power shaft to crank the engine, and means for automatically disengaging the member from the sprocket gear, in combination with means operated 100 by the sprocket gear on the power shaft and connected to said member for rotating the latter in the opposite direction to store up energy in the power spring, and means for operatively connecting the first mentioned gear with and disconnecting the same from the engine shaft respectively at the beginning of the cranking operation and after energy has been restored in the spring. 110

16. In a starting apparatus for explosive engines, an engine shaft, a sprocket gear mounted upon and adapted to be operatively connected to said shaft, cranking means operatively connected to said fixed gear, comprising a spring actuated power shaft, a sprocket 120 gear rotatably mounted upon said power shaft and operatively connected to the aforesaid gear, a clutch member fixed to said shaft but longitudinally movable thereon, rotatable means on said shaft normally in inter- 125 130

- locking engagement with said clutch member, means for normally holding the aforesaid means against rotation, and means for moving the clutch member out of interlocking engagement with said rotatable means into clutching engagement with the sprocket gear on the power shaft, whereby said gear is actuated by the power means to rotate the sprocket gears to crank the engine, in combination with means to store up energy in the spring, comprising a toothed gear rotatably mounted adjacent to the power shaft and actuated by the sprocket gear on the last mentioned shaft, and means operatively connecting the toothed gear with the holding mechanism and actuated by the toothed gear to rotate the holding mechanism and clutch member in the opposite direction to store up energy in the power spring.
- 10 17. In a starting apparatus for explosive engines, an engine shaft, means for operatively connecting said gear with said engine shaft, a sprocket gear rotatably mounted adjacent and operatively connected to the aforesaid sprocket gear, a spring actuated power means adapted to engage with said second mentioned sprocket gear and actuated in one direction to rotate the same to crank the engine, and means connecting the second mentioned sprocket gear to the power means and operated by said sprocket gear after the engine has been cranked for actuating the power means in the opposite direction to restore energy in the power means,
- 15 35 said connecting means normally serving to hold the spring actuated means against rotation.
18. In a starting apparatus for explosive engines, an engine shaft, a sprocket gear loosely mounted upon said shaft, means for operatively connecting said gear with said engine shaft, a second sprocket gear rotatably mounted adjacent and operatively connected to the first mentioned gear, in combination with spring actuated means for engaging with the second mentioned sprocket gear and rotated in one direction to crank the engine, and means actuated by the engine after the same has been cranked to restore energy in the power spring, comprising mechanism connected to the second mentioned sprocket gear and engaging the spring actuated means to rotate the same in the opposite direction, said mechanism adapted to hold the spring actuated means normally stationary against the tension of the power spring.
- 20 40 45 50 55 60 65 70 75 80 85 90 95 100 105 110
19. In a starting apparatus for explosive engines, an engine shaft, a sprocket gear loosely mounted upon said shaft, means for operatively connecting said gear to said engine shaft, a second sprocket gear rotatably mounted adjacent and operatively connected to the aforesaid sprocket gear, spring actuated means adapted to operatively connect to the aforesaid sprocket gear, and adapted to be rotated in one direction to crank the engine, in combination with mechanism operated by the sprocket gear after the engine has been cranked to rotate the spring actuated means in the opposite direction to restore energy in the power shaft.
20. In a starting apparatus for explosive engines, an engine shaft, a sprocket gear loosely mounted upon said shaft, means for operatively connecting said gear to said engine shaft, a second sprocket gear rotatably mounted adjacent and operatively connected to the aforesaid sprocket gear, spring actuated means adapted to operatively engage with the second mentioned sprocket gear and adapted to be rotated in one direction to crank the engine, in combination with mechanism operated by the sprocket gear after the engine has been cranked to rotate the spring actuated means in the opposite direction to restore energy in the power shaft, said restoring mechanism normally engaging with the spring actuated means to hold the same stationary against the tension of the power spring.
21. In a starting apparatus for explosive engines, an engine shaft, a sprocket gear mounted thereon and adapted to be operatively connected thereto, a power shaft located adjacent to said engine shaft, a counter shaft located in proximity to the power shaft, a sprocket gear rotatably mounted upon the power shaft and operatively connected to the sprocket gear on the engine shaft, a toothed gear fixed upon the counter shaft and operatively connected to the sprocket gear, spring actuated means adapted to engage with the sprocket gear on the power shaft and to be rotated in one direction to crank the engine, and mechanism adapted to engage with the spring actuated means and operated by the toothed gear to rotate the spring actuated means in the other direction to restore energy in the power shaft.

In testimony whereof we affix our signatures in the presence of two subscribing witnesses.

GEORGE S. THOMPSON.
CHARLES F. RICHARDSON.

Witnesses for Thompson:

WM. BOHLEBER,
JOHN B. MCGUIRE.

Witnesses for Richardson:

ROY J. SOULER,
LESTER B. BROWN.
